WILLIAM J. McLEA, OF BUFFALO, NEW YORK, ASSIGNOR TO HIMSELF AND
C. F. YOUNG, OF THE SAME PLACE.

Letters Patent No. 76,789, dated April 14, 1868.

IMPROVEMENT IN GAS-REFLECTORS.

The Schedule referred to in these Letters Patent and making part of the same.

TO ALL WHOM IT MAY CONCERN:

Be it known that I, WILLIAM J. McLEA, of Buffalo, in the county of Erie, and State of New York, have invented a new and useful Improvement in Gas-Light Reflectors; and I do hereby declare that the following is a full, clear, and exact description thereof, which will enable others skilled in the art to make and use the same, reference being had to the accompanying drawings, forming part of this specification, in which—

Figure 1 is a view of my improved-reflectors in one position, one being removed to show the operating-apparatus.

Figure 2, a view of the same in another position.

Similar letters of reference indicate like parts.

This invention relates to an improvement in the construction of gas-light reflectors, and consists in connecting ordinary reflectors with an apparatus of jointed and sliding rods, and pliant gas-tubes, in such a manner that the reflectors may be moved in their position as desired, for the reflection of light at different degrees of depression or elevation. By the employment of this apparatus a great increase of light is obtained from the gas, and consequent economy in its consumption.

A represents a gas-chamber or feed-fountain, which is to be connected at the lower end with an ordinary gas-pipe, wherever the reflectors are required, as shown in the drawings. The chamber A has a cap-piece, B, and is surmounted with a vertical rod, a, with a knob-head, b, and which has fitted on it a slide-piece, C, which is moved up and down on the rod by means of a rod, c, that passes through guides e e, at the top and bottom of the gas-chamber A. D D are gas-reflectors, made of polished metal, as usual, which are suspended by rods d d, fastened in the middle at their back, and hinged to the cap-piece B, so that they shall have a vertical movement; and at their upper part also, by links g g, that are hinged at one end to lugs h' h', on the back of the reflectors, and at the other end to projections on the slide C, so that they also shall have a vertical movement directly in line with the connecting-rods d d, with which they may thus move up and down in concert, to elevate or depress the reflectors, as the slide C is raised or lowered on the upright rod a, by a sliding rod, c.

At the bottom of the chamber A are nipple gas-vents, i.e., as many in number as may be required by the reflectors, and on each nipple is fastened an India-rubber tube, m, which leads the gas to the rear end of a burner, k, introduced in each reflector D. This construction of the gas-chamber A, with vents at the bottom, tends to break the rush of gas directly out of the vents, and to secure a steady light by a regular flow of the gas.

It will be seen that by this arrangement of apparatus connected with the gas-chamber A and the reflectors D, the reflectors may be raised or lowered at any angle of elevation or depression, to throw the light upon any desired point within range.

My invention is not confined to the shape and number of the reflectors attached to one gas-chamber, nor to the position of the sliding-rod, as that may move horizontally, as well as vertically, nor to the particular device for operating the rod, as a screw, lever, or eccentric, may be employed to produce the same movement.

Having described my invention, I claim as new, and desire to secure by Letters Patent—

The combination of the gas-chamber A, the rod a, the slide C, the sliding rod c, the reflectors D, and the rubber gas-tubes m, constructed, arranged, and operating substantially as and for the purposes herein described.

WILLIAM J. McLEA.
